CLAIM

The ornamental design for a degreaser ventilation hood, as shown and described.

[21] Appl. No.: 377,630

DESCRIPTION

[22] Filed: May 13, 1982

FIG. 1 is a top plan view of a degreaser ventilation hood embodying my new design;

[52] U.S. Cl. D23/151
[58] Field of Search D23/151; 55/443, 444;
126/299 D; 98/115 K, 121 R

FIG. 2 is a front elevational view thereof;

FIG. 3 is a rear elevational view thereof; and

FIG. 4 is a right side elevational view thereof, the left side being a mirror image of the right side shown.
